PORTABLE POWER ATTACHMENT FOR HAND STOCKS AND PIPE DIES

Filed July 1, 1922

Fig. 1.

Patented May 19, 1925.

1,538,096

UNITED STATES PATENT OFFICE.

STEPHEN CORNELIUS DOEHRING, OF HOUSTON, TEXAS.

PORABLE POWER ATTACHMENT FOR HAND STOCKS AND PIPE DIES.

Application filed July 1, 1922. Serial No. 572,244.

To all whom it may concern:

Be it known that I, STEPHEN C. DOEHRING, citizen of the United States, residing at Houston, in the county of Harris and State 5 of Texas, have invented certain new and useful Improvements in Portable Power Attachments for Hand Stocks and Pipe Dies; and I do hereby declare the following to be a full, clear, and exact description of the invention, such as will enable others skilled in the art to which it appertains to make and use the same.

This invention relates to pipe threading tools, and has for its object to provide 10 mechanism which will permit the ordinary pipe dies to be power driven.

The invention consists of an annular frame or housing within which is supported a ring gear, the gear being driven by suitable power mechanism supported on the housing, the die being carried in a stock which is connected to the gear in a manner hereinafter specified. The annular frame is provided with handles to permit handling.

The various features of novelty and invention will appear from the detailed description taken in connection with the accompanying sheet of drawing forming part of this specification, and in which:—

Figure 1 is a plan view of the improved device;

Fig. 2 is a section on line 2—2 of Fig. 1, and

Fig. 3 is a fragmentary view on an enlarged scale of certain details.

Referring to the drawings, 10 designates a die stock or frame of any suitable form, which is to be power driven. Extending radially from the frame 10 is a plurality of conventional handles or spokes 12, these being connected to the frame 10 in any suitable manner as by being mounted in sockets 13. 14 is a ring gear having inwardly projecting sockets within which the outer ends of the spokes 12 are secured, said spokes being removably mounted in said sockets as by clamp plates 15.

The ring gear is supported in a housing 16 which is preferably made in two parts 16^a and 16^b, the two parts having radial lugs 17 through which are passed suitable securing members 18. The housing is open at its inner periphery and has angular flanges or ledges 19 which are adapted to enter grooves 20 in the side faces of the gear 14, in a manner to support the gear and

permit it to turn within the housing. It will be observed that the clamps 15 which secure the outer ends of the arms 12 to the gear 14 are located outside of the housing, 60 the gear being preferably provided with inwardly extending lugs 14' to which said clamps are secured.

Mounted on the housing is a shelf or support 21 on which is mounted a motor 22, 65 and a worm 23 is supported in suitable bearings 24 on the housing. 25 is the connecting shaft between the motor and worm and 26 is the cover extending over the worm. Extending from the housing are handle 70 members 27 by which the device is handled. A hook 28 pivotally connected to the housing as at 29 allows the device to be suspended if desirable.

When it is desired to thread a pipe by the 75 improved power attachment, the die stock is slipped on pipe. The device can be suspended from the hook 28 and held by the handles 27 or the device can be supported on the standards as shown. Power applied 80 to the motor rotates gear 14. In small dies only one set of spoke handles need be connected to the gear but provision may be made on the gear ring for four or more such spoke handles.

I have shown the gear 14 as driven by a worm, but this is merely for illustrative purposes. It is contemplated that if found desirable, the gear may be driven by a bevel pinion instead of a worm.

It will now be seen that the housing and gear 14 are so coordinated that the gear is supported in a simple and efficient manner, and at the same time the ledges 19 and 20 on the housing prevent the entrance of dirt 95 and chips into the housing where it would cause damage to the moving parts. The invention is relatively simple but is of great usefulness to plumbers and others having occasion to use large pipe dies.

What I claim is:

1. The combination of a ring gear having an annular groove in each side face and a plurality of cutouts formed inwardly of the said grooves, clamping blocks removably secured over said cutout to secure radially extending members, a two-part housing enclosing said ring outwardly of said clamping blocks and having inwardly directed ledges received in said grooves, said ring being 110 turnable in the housing and gear mounted in said housing for driving said gear.

2. In combination, a ring gear, means on the inner periphery of said gear to which spoke-like members may be secured, a housing within which said gear is mounted, said gear having inwardly directed opposed ledges which are received within annular grooves in the sides of the gear, means

for driving said ring gear including a gear meshing with the ring gear and extending through the housing, said housing having radial arms by means of which the same may be supported.

In testimony whereof I affix my signature.

STEPHEN CORNELIUS DOEHRING.
